UNITED STATES PATENT OFFICE.

THOMAS TAYLOR, OF SAVILLE MILL, BOLTON, ENGLAND, ASSIGNOR TO T. TAYLOR LIMITED,
OF SAVILLE MILL, BOLTON, ENGLAND.

WOVEN FABRIC.

No. 922,641.

Specification of Letters Patent. Patented May 25, 1909.

Application filed January 15, 1908. Serial No. 410,975.

To all whom it may concern:

Be it known that I, THOMAS TAYLOR, a subject of the King of Great Britain, residing at Saville Mill, Bolton, in the county of 5 Lancaster, England, have invented new and useful Improvements in Woven Fabrics, of which the following is a specification.

My invention relates to improvements in the manufacture of woven figured fabrics 10 and particularly to woven figured fabrics having a plain ground and a raised plain figure woven by the use of a jacquard and two heald shafts, the jacquard and heald shafts being used to form the ground and the 15 heald shafts only to form the figure, and my improvements consist essentially in my particular method of weaving such raised figured fabrics with one warp only (by preference) and with one weft from a single 20 shuttle, drawing one third of the warp yarn into two healds for binding the weft in the raised figure, and drawing the remaining two thirds of the warp yarn which floats underneath the figure into the jacquard harness for the weaving of the ground and interweaving both the warp yarn from the 25 healds and the warp yarn from the jacquard harness with the weft into a plain cloth ground having a raised plain cloth figure 30 substantially as hereinafter described with reference to the accompanying sheet of diagrams in which—

Figure 1 is a diagram representing the drawing-in of the yarn into the jacquard harness and healds. Fig. 2 is a diagram representing the order of shedding, X signifying up, and the numerals 1, 2, 3, 4, denoting picks. Fig. 3 is a transverse section taken across the warp of my improved 40 woven figured fabric. Fig. 4 is a diagrammatic longitudinal section taken across the weft and showing all the warp ends.

In carrying out my invention I use only one weft from a single shuttle and by preference only one warp, of one count of yarn; but I use both a jacquard machine and two heald shafts and draw portions of the warp ends into each, as shown in Fig. 1, but none 45 into both the jacquard harness and the healds. The jacquard harness is tied up in pairs in such a manner that two ends are worked by one and the same hook and this gives a bolder stitch and effect in defining the figure of the cloth.

The yarn worked by the jacquard consists 55 of two thirds of the whole warp and this yarn weaves only in the making of the ground (together with the yarn in the healds as herein-after described) and floats underneath the figure, not being interwoven in the figure 60 part. The remaining one third of the warp is drawn into two healds and this portion of the warp alone interweaves with the weft to make a plain cloth figure. This portion of the warp also interweaves with the two 65 thirds in the jacquard harness in such a manner that the whole of the warp, both jacquard and heald portions, makes a plain ground to the cloth, with a plain figure upon it made by one third of the warp only (together with 70 the weft) as previously described and as illustrated by the diagrams.

It will be seen from the extended Fig. 1 that there are twice as many ends in the jacquard harness as in the healds and that 75 the ends in the two healds are drawn alternately on the heald staves so that each heald end divides one of the two pairs of harness threads each pair of which is tied to one hook, the three ends, *i. e.*, two jacquard ends 80 divided by one heald end, are all drawn through the same dent in the reed, not shown; the ends in the healds form a plain cloth on the figure, and also combined with the ends in the harness make a plain weave of 85 the whole ends of the warp in the ground.

From Fig. 2 it will be seen that the jacquard is up at every pick but it falls and rises to change cards between each pick and to raise one half of the yarn in the harness 90 where the ground is required at one pick, and the other half of the yarn in the harness where the ground is required, at the other pick; where figure is required the jacquard does not lift any yarn. One half the yarn in 95 the healds is raised each pick and in the ground combines with the yarn in the harness to make the plain ground, but in the figure the yarn in the healds makes a plain cloth on the figure, the yarn in the harness 100 not being raised by the jacquard under the figure but floats at the back of the figure, as shown best in the diagram, Fig. 3.

What I claim and desire to secure by Letters Patent of the United States is:—

The new or improved woven figured fabric 105 in which the ground is a plain weave composed of the whole of the warp yarn inter-

woven with the weft, and the raised figure is also a plain weave composed of one third only of the warp yarn interwoven with the weft, while the remaining two thirds of the warp yarn is floated underneath the raised figure substantially as herein described.

In testimony whereof I have signed my

name to this specification in the presence of two subscribing witnesses.

THOMAS TAYLOR.
